UNITED STATES PATENT OFFICE.

WALTER P. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,255,929.

Specification of Letters Patent. Patented Mar. 12, 1918.

Application filed May 15, 1916. Serial No. 37,478.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to roof sheets for inside, outside, and single-course car roofs, and particularly to a roof sheet which is composed largely of pulp or fiber pressed into the required shape and reinforced with metal around the edges.

The object of the invention is to reduce the first cost and prolong the life of car roofs of the type which heretofore have been composed entirely of sheet metal by combining fiber or pulp board with the metal portions of the roof sheets, and thereby reducing the amount of sheet metal required and protecting it from rust.

The invention consists in the construction of the roof sheets partly of pressed or rolled sheets of pulp, fiber, gypsum, or the like, and in the form of the sheets and their arrangement in the car roofs. The invention further consists in the details of the car roof shown in the drawings and herein-after described.

Further objects of the invention appear in connection with the description of the car roof shown in the drawings, and what the invention consists in is more particularly defined in the appended claims.

In the drawings, wherein the same reference characters designate similar parts in the several views,

Figure 1 is a plan view of a portion of a car roof, partly broken away to disclose the construction of the under side of the roof; Fig. 2 is a vertical transverse section through the ridge portion of the roof, on the line 2-2 in Fig. 1;

Fig. 3 is a plan view of the metal skeleton of a roof sheet ready for the pulp or fiber to be molded in place;

Fig. 4 is a vertical transverse section through the eaves portion of the roof, on the line 4-4 in Fig. 1;

Fig. 5 is a vertical cross-section through a carline and seam or joint between two roof sheets, on the line 5-5 in Fig. 1; and

Fig. 6 is a view similar to Fig. 4, showing a modified form of eaves construction.

For purpose of illustration, the drawings 55 show the invention applied to a single-course roof, that is, a roof having no sheathing boards, there being only one layer or course of sheathing material covering the roof framework; but the invention can be 60 applied to roofs having sheathing boards in addition to the roof sheets, which may be arranged either above or below the sheathing boards.

In the construction shown in the drawings, the roof framework consists of metal carlines 10 which span the car from one side plate 11 to the other at intervals apart of two to three feet or more, and which support the wood purlins 12 and ridge pole 13 70 which run from end to end of the car.

The roof sheets 14 are arranged in pairs on opposite sides of the roof, and rest upon the side plates, purlins, and ridge pole. The roof sheets are composed of fibrous or light 75 cementitious material which can be pressed, rolled or otherwise molded in place about a suitable framework 15 of metal. Preferably, the side edges of the framework are metal strips, the outer margins of which are 80 flanged up and turned in over the body portion to form side marginal flanges 16. These side flanges 16 hook into the side walls of inverted channel-shape seam covers 17 which straddle the flanges of adjacent roof sheets 85 and the side walls of which have their lower edges turned under and down to form flanges 18 which hook under the side flanges 16 of the roof sheets.

The ridge end of the frame 15 of the roof 90 sheet has a similar marginal flange 16 for hooking into the turned under lower edge 20 of one of the side walls of the ridge seam cover 19. The eaves end of the frame 15 of the roof sheet projects beyond the molded 95 material and is turned under, forming a flat fold or flange 21 which engages with a flat fold or flange 22 on the top edge of the eaves flashing strip 23. Near the ridge end of each roof sheet, at the middle of its under 100 side, is a circular boss or projection 24 which fits into a recess 25 in one end of a metal strap 26 which is secured across the ridge for pivotally holding each pair of roof sheets. The under side of the boss 24 105 is protected by a sheet metal cup 27, which is molded into the material of the body of the sheet. Wire mesh 28 or other suitable

reinforcement may be secured to the frame 15 and molded into the roof sheet to strengthen it.

The side seam covers 17 are supported on 5 wood battens 29 which are bolted or otherwise secured to the purlins and ridge pole. The ends of the seam covers 17 and the eaves ends of the roof sheets are held down by metal clips 30 which are bolted or otherwise 10 secured to the side of the car. The ridge ends of the side seam covers 17 and the ends of the ridge seam covers 19 are covered by ridge corner caps 31 which are secured to the ridge pole by bolts. The running boards 32 are supported on wood saddles 33 which rest on the ends of the side seam covers and battens and are held in place by the same bolts which secure the corner caps.

20 The pivot bosses 24 of the roof sheets may be pinned to the metal straps 26 by bolts or studs 34 which are embedded in the material of the roof sheets and the lower ends of which project through holes in the cup portions 25 of the straps. The lower ends of the studs 34 may be held in place in their holes by washers and cotter pins as shown in Fig. 2, or by other suitable means.

It is evident that various plastic or cementitious materials may be used for the body 30 portion of the roof sheet, and the invention is not restricted to any particular material except that it should be fireproof and a non-conductor of heat. Moreover, it is evident 35 that modifications may be made in the form and arrangement of the roof sheets and in the flexible seams connecting the roof sheets, without departing from the invention; and the invention is not restricted to the specific 40 details shown in the drawings.

I claim the following as my invention:

1. A car roof comprising roof sheets having metallic frame-work and edges and a main body portion of fibrous material, the 45 side and ridge margins of each sheet being turned up to form flanges, seam covers of inverted channel shape having flanges co-operating with the side flanges of said roof sheets, and a ridge cover of inverted channel shape having flanges to co-operate with the ridge flanges of said roof sheets.

2. A car roof comprising a ridge pole, a saddle secured to said ridge pole, roof sheets of cementitious material having edges of 50 metal, each of said roof sheets having a metallic projection near one margin, said saddle having depressions, each of which co-operates with one of said projections to pivotally retain the roof sheet in position, 55 and bolts for fastening said roof sheets to said saddle.

3. A car roof comprising a ridge pole, a saddle secured thereto, roof sheets of cementitious material reinforced with metal, said 60 metal reinforcement protruding from the

cementitious material at the sides and ends and being turned up to form side, ridge, and eaves flanges, means for pivotally attaching said roof sheets to said saddle, and covers for said side, ridge, and eaves flanges.

4. A car roof comprising roof sheets of heat insulating materials of the kind described, said sheets having a reinforcing member of wire mesh embedded therein and having metallic edges, the eaves edges of 75 said roof sheets being folded back on their under sides to form a flat flange, and a metal eaves flashing having a flat flange interlocking with said flat flanges of said roof sheets.

5. A car roof comprising a supporting structure, roof sheets of molded fibrous material pivotally secured to said supporting structure, said roof sheets having a metallic reinforcing member embedded therein and 85 having metallic margins, said margins having upwardly extending flanges at the sides and ridge end of the sheets and rebent flanges at the eaves end of the sheets, inverted channel shape seam covers having 90 inside flanges interlocking with said side flanges of said roof sheets, a ridge cover having inside flanges interlocking with said ridge flanges of said roof sheets, and an eaves flashing strip having a flange interlocking with said rebent flanges of the roof sheets.

6. A car roof comprising a substructure, said substructure comprising carlines, purlins and ridge pole, said ridge pole having a 100 metallic saddle having a series of depressions, roof sheets of molded fibrous material, having metallic edges and metallic projections on the middle of their under sides near the ridge pole, the side and ridge edges of 105 said roof sheets being turned up to form flanges, seam covers of inverted channel shape resting on said carlines and having inside flanges fitting loosely into the side flanges of the roof sheets, and a ridge cover 110 of inverted channel shape having inside flanges fitting loosely into the ridge flanges of the roof sheets, each of said above-mentioned projections on the roof sheets fitting into one of the depressions of the supporting member whereby the roof sheets are pivotally secured in position.

7. A car roof comprising roof sheets whose marginal portions consist of metal members partially embedded in a plastic 120 body portion, said marginal portions being shaped to form seam members and the body portion having a metal pivot cup molded therein.

8. A car roof comprising roof sheets consisting of reinforced fibrous material and a marginal metal portion partially embedded in said body portion, the projecting part of said marginal portion being shaped into rebent flanges to constitute seam members, the 125

flanges on three sides of the sheet being above the body thereof and the flange of the fourth side being below said body.

9. A car roof comprising roof sheets consisting of reinforced fibrous material, a marginal metal portion partially embedded in said body portion, the projecting part of said marginal portion being shaped into rebent flanges on three sides of the sheet to 10 constitute seam members extending above the body portion, and seam covers having

counterpart seam members to engage the flanges on adjacent sheets, the marginal metal portion on the fourth side of said sheet extending below the body portion and 15 being close to the eaves of the car; and a flashing strip at the eaves engaging said last mentioned flange.

Signed at St. Louis, Missouri, the 11th day of May, 1916.

WALTER P. MURPHY.
